UNITED STATES PATENT OFFICE.

IRVING CARSON, OF BARBERTON, OHIO, ASSIGNOR TO THE DIAMOND MATCH COMPANY, OF CHICAGO, ILLINOIS, A CORPORATION OF ILLINOIS.

INKING MECHANISM FOR PRINTING PRESSES.

Application filed June 6, 1927. Serial No. 196,757.

This invention relates to printing presses, and more especially to presses of the "Kelly" type, wherein a continuously rotating cylinder makes two revolutions for each reciprocation of the bed, the cylinder being lowered for the printing stroke of the bed and raised during the return stroke. The present invention concerns especially the inking mechanism of the press, my object being to effect a uniform distribution of ink of different colors on the inking rolls in such a manner that the uniform impression of a sheet with adjoining longitudinal sections of different colors, respectively, may be had, as required, for example, in the printing of cardboard sheets that are subsequently subdivided into match book covers.

To this end my invention comprises a novel construction, arrangement and operation of the rolls of the inking mechanism, as will be hereinafter described and claimed.

In the drawings—

Figure 1 is a side elevation of a portion of a Kelly press embodying my invention.

Fig. 2 is a transverse vertical section of the press, as on the line 2—2 of Fig. 1.

Fig. 3 is a longitudinal vertical section through the fountain and rolls of the inking mechanism, as on the line 3—3 of Fig. 2.

Fig. 4 is a partial plan of the fountain and adjacent rolls.

Referring to the drawings, 11 designates a part of the supporting frame of a Kelly press; and 12 designates the reciprocating bed on which the type form is mounted.

13 designates the ink fountain which is supported by suitable brackets 14 on the side of the main frame, and 15 designates the intermittently rotatable ink delivery roll, which extends longitudinally of and constitutes the back of the fountain.

The shaft 16 of this roll has fast thereon, at one end, a ratchet wheel 17 with which engages a pawl 18 carried by one arm of a bell crank 19 loosely hung on the shaft 16. The other arm of the bell crank is connected by means of a rod 20 with a lower rock-arm 21, the shaft 22 of which latter is journaled in a bracket 23 on one side of the main frame. This shaft 22 has secured thereto an actuating arm 24, the roll 25 whereof is held in operative contact with a suitable cam 26 on a driven shaft 27 of the press by means of a retracting spring 28 secured to the rock-arm 21 and the main

frame. Hence during the rotation of the shaft 27 intermittent motion is transmitted therefrom to the ink delivery roll 15. 29 designates the oscillatory ductor roll, which is movable back and forth between the delivery roll and the first ink distributing roll 30, which latter, together with the succeeding distributing rolls 31, 32, are mounted to rotate in a frame 33 which overhangs the freely rotatable inking rolls 34, 35, 36. The shafts 30', 31', and 32' of the distributing rolls 30, 31, 32 are geared together for continuous rotation, as usual, the distributing roll 30 contacting with the inking roll 34 and the distributing roll 32 contacting with the inking rolls 35 and 36.

The shaft 37 of the ductor roll is supported at its ends on rocker arms 38, the shaft 39 of which is journaled in the adjacent side bracket 14. On one end of this shaft is an arm 40 which is connected by means of a rod 41 with a lower rock arm 42 whose shaft 43 is journaled in the bracket 23. This shaft 43 is provided with an actuating arm 44 having a roll 45 which is held in operative contact with a suitable cam 46 on the driven shaft 27 by means of a suitably disposed retracting spring 47. Hence during the rotation of the shaft 27, oscillatory motion is imparted to the ductor roll, which transfers the ink from the delivery roll 15 to the first distributing roll 30.

The shafts of the inking rolls 34, 35, 36 are journaled in bearings in brackets 48 located at the respective sides of the main frame, and these rolls are positioned to contact with the type form as usual.

Heretofore the surfaces of the distributing and inking rolls have been continuous or uninterrupted from end to end, and the two distributing rolls 30, 32 have had capacity for longitudinal reciprocation within limits in order to effect the uniform distribution of the ink on the peripheries of the series of distributing rolls preparatory to its transmission to the respective inking rolls. The means for reciprocating the rolls 30, 32 included a vibratory lever 49 the upper end of which was detachably connected with circumferentially grooved blocks on the adjacent ends of the shafts 30', 32' of said rolls 30, 32 respectively. The block on the shaft 30' is shown at 49'. The lever 49 was connected at its lower end by a detachable pin 50 to one end of a rod 51 operatively con-

nected by a strap to an eccentric 52 on the driven shaft 27.

The Kelly press embodying the foregoing described construction was primarily employed for single color printing, but when two-color printing of the character previously mentioned was desired, the ink fountain 13 was divided into two chambers for the reception of the respective colors, by means 5 of a partition 53 inserted in the mid section of the fountain, and the pin 50 at the lower end of the lever 49 was removed so as to disconnect the lever from the eccentric rod and prevent longitudinal reciprocation of the 10 rolls 30, 32; it being obvious that such reciprocatory motion, if permitted, would cause the overlapping and mixing of the different color inks on the respective portions of the rolls. However, the absence of 15 the longitudinal motion of the distributing rolls results in an uneven distribution of the ink on the inking rolls, and in consequence the impression varies on and throughout the 20 respective sections of the sheet. Moreover, owing to the continuity of the opposing surfaces of the rolls the colors tend to run together and overlap midway between the ends 25 of the distributing rolls.

According to my invention, I adapt the 30 press to double-color printing in which the objections hereinbefore mentioned are avoided, as follows: The fountain 13 is divided, as previously, into two chambers by means of the partition 53, but the connection 35 between the lower arm of the lever 49 and the eccentric rod 51 is undisturbed. The pivotal block connection between the upper arm of the lever and the shaft 32' of the roll 32 is removed, and that between the 40 lever and the shaft 30' of the roll 30 is retained. Hence the roll 32 simply rotates without longitudinal reciprocation, while the roll 30 is given longitudinal reciprocation as well as rotary motion. The ductor 45 roll 29 and the distributing roll 31 and the first printing roll 34 are formed midway between their ends with circumferential grooves 54, 55, 56, respectively, each of which divides the proximate roll surface into two sections adapted to receive and segregate the 50 respective colors; that is to say, the ductor roll receives from the delivery roll the differently colored ink, well spaced apart, and transfers the two separated colors to the uninterrupted 55 surface of the roll 30, which, in turn, applies the ink to the respective opposing surfaces of the inking roll 34, and also to the interrupted surfaces of the distributing roll 31. The latter roll in turn applies the ink to the uninterrupted surface of the roll 32, which thereupon transfers the ink to the respective contacting inking rolls 35, 36.

The width of each of the grooves 54, 55, 56 is equal to the extent of longitudinal movement of the roll 30, or substantially so, and

therefore such roll 30 effects the uniform distribution of each color on the opposing paired surfaces of the rolls 31, 34. Likewise the surfaces of the roll 31 effect the uniform transfer of the ink on the distributing roll 32, which correspondingly applies the ink to the inking rolls 35, 36. Consequently there is no liability of the colors overlapping at the middle of the rolls.

The foregoing described roll construction and operative arrangement embodying my invention, although simple and inexpensive, have solved the problem of uniformly printing two different color sections in close lateral relation throughout the sheet.

I claim—

1. Inking mechanism for printing presses having a fountain with separate ink chambers and having also associated distributing and inking rolls, said distributing rolls comprising a plurality of rolls presenting uninterrupted ink-receiving surfaces, and also an intermediate roll having spaced-apart ink-receiving surfaces in peripheral contact with the surfaces of the laterally adjacent rolls, means for delivering the ink in spaced relation from the respective chambers of the fountain to the surface of one of the said adjacent rolls, and means for longitudinally reciprocating the latter roll in a path substantially equal in length to the width of the gap between the spaced ink-receiving surfaces.

2. Inking mechanism for printing presses having a fountain with separate ink chambers and having also associated distributing and inking rolls, said distributing rolls comprising a plurality of rolls presenting uninterrupted ink-receiving surfaces, and also an intermediate roll having spaced-apart ink-receiving surfaces in peripheral contact with the surfaces of the laterally adjacent rolls, a ductor roll operative between the fountain and one of the said adjacent distributing rolls and having spaced-apart ink-receiving surfaces corresponding with those of the intermediate distributing roll, and means for longitudinally reciprocating the said adjacent roll in a path substantially equal to the length of the gap between the spaced ink-receiving surfaces.

3. In inking mechanism for printing presses, the combination with a fountain having separate ink chambers, of a ductor roll having spaced-apart peripheral surfaces for receiving ink from the respective chambers, two ink distributing rolls having uninterrupted peripheral surfaces to one of which the ink is transferred from the fountain by the ductor roll, an intermediate ink distributing roll having spaced-apart surfaces corresponding with those of the ductor roll, means for longitudinally reciprocating the distributing roll with which the ductor roll co-acts, the reciprocating stroke being sub-

stantially equal in length to the width of the space between the ink-receiving surfaces of the intermediate roll, an inking roll in peripheral contact with the reciprocative distributing roll and having spaced-apart ink-receiving surfaces corresponding with those of the ductor roll, and two inking rolls having uninterrupted peripheral surfaces in contact with the second of said two distributing rolls.

Signed at Barberton, in the county of Summit and State of Ohio this 2nd day of June, A. D. 1927.
